ADJUSTABLE HOLDBACK FOR CRUCIBLES.
APPLICATION FILED SEPT. 29, 1913.

Patented June 2, 1914.

2 SHEETS-SHEET 2.

UNITED STATES PATENT OFFICE.

HERMAN BEULKE, OF NEW CASTLE, PENNSYLVANIA, ASSIGNOR TO AMERICAN CAR AND SHIP HARDWARE MANUFACTURING COMPANY, OF NEW CASTLE, PENNSYLVANIA, A CORPORATION.

ADJUSTABLE HOLDBACK FOR CRUCIBLES.

1,098,470.

Specification of Letters Patent.

Patented June 2, 1914.

Application filed September 29, 1913. Serial No. 792,444.

To all whom it may concern:

Be it known that I, HERMAN BEULKE, a citizen of the United States, residing at New Castle, in the county of Lawrence and State 5 of Pennsylvania, have invented certain new and useful Improvements in Adjustable Holdbacks for Crucibles, of which the following is a specification, reference being had to the accompanying drawings.

10 This invention relates to new and useful improvements in supporting devices and more particularly to a supporting device or hold-back for crucibles, used in connection with machines or devices for pouring molten 15 metal and the primary object of the device is to provide an improved hold-back which is capable of application to crucibles of various sizes.

20 A further object of the invention resides in providing a device which may be quickly and readily applied to any shank used for supporting crucibles and a still further object resides in providing a device which is simple and durable in construction, inexpensive to manufacture and one which will 25 be very efficient and useful in operation.

With these and other objects in view, the invention consists in the novel features of construction, combination and arrangement 30 of parts as will be hereinafter referred to and more particularly pointed out in the specification and claims.

In the accompanying drawings forming a part of this application, Figure 1 is a side 35 elevation of the improved device showing the manner in which the same is applied to use. Fig. 2 is a plan view thereof. Fig. 3 is an enlarged detail side elevation of the device. Fig. 4 is a front elevation of the 40 same. Fig. 5 is an enlarged detail plan view of the device. Fig. 6 is a vertical section through the sliding block used on the device. Fig. 7 is a front elevation of my 45 device removed, showing parts in section; and Fig. 8 is a side elevation of a slightly modified form of the device.

In describing my invention, I shall refer to the drawings in which similar reference characters designate corresponding parts 50 throughout the several views and in which—

1 indicates a crane-bail, such as used in overhead devices, in the arms of which are rotatably mounted the arms 2 of a supporting shank, said arms engaging with a

circular or ring-like member 3, which directly receives therein a crucible 4.

55 My invention contemplates the provision of a means for retaining the crucible in an upright position and, to this end, I provide my improved hold-back or supporting member. The same consists of a split ring 5, applicable to one of the arms 2 of the shank, said ring pivotally retaining between the free ends thereof one end of a rod or arm 6. Joined to the opposite end of the arm or 60 rod 6, in any manner desired, is a Y-shaped portion 7 which is curved downwardly and thence upwardly to form a straddling outer end portion on the device, the outer arms of 65 said straddling portion 7 being arranged 70 vertical and parallel, as shown at 8.

A clamping device is provided for adjustable engagement with the vertical arms 8 of 75 said straddling portion, consisting of a pair of inverted L-shaped arms which are arranged to contact respectively with the inner opposed faces of the arms 8, said L-shaped arms 9 being secured at their lower ends to the transverse strips or plates 10 which are 80 arranged in engagement with opposite faces 85 of the vertical arms 8. The upper ends of the inverted L-shaped arms 9 are held in proper position with respect to one another by means of a pin 11, on which is mounted a spacing sleeve 12. This substantial clamping 90 device is, as will be seen from the construction disclosed, slidably arranged between the arms 8, the upper hooked portion thereof being adapted for engagement with the upper end of the crucible 4. In order 95 to retain this clamping portion in any adjusted position, the arms 8 are provided with alining horizontal slots or channels 13 and the lower portions of the arms 9 are provided with similar slots or channels 14, adapted to register therewith. A pin or bolt 15 is adapted to be disposed through the registering channels or slots 13 and 14, whereby said arms 9 will be held in any adjusted position with respect to the arms 8. 100 From this construction, it will be seen that the device is applicable for use to crucibles of various sizes.

In applying the device, it will be seen 105 that the straddling portion 7 on the one end of the arms 8 will straddle the one arm 2 of the shank and the hooked ends of the arms 9 are designed for engagement with the up-

per end of the crucible. In order to lock the arm 6 securely in engagement with the arm of the shank, the rings 16 and 17 are provided and through the inclination of the 5 arm 6, when the device is positioned, it will be seen that said rings may be forced into frictional engagement with said arm and the arm of the shank. Thus through this 10 medium the crucible may be securely held in position in the circular portion 3 of the shank, at all times.

Slidably mounted on the arm 6, is a block 18, the upper end of which is slotted to provide ears 19 and pivotally mounted between 15 these ears is the bail holder 20. This bail holder consists of an arm which is bifurcated or forked to straddle the one arm of the bail and said bail holder is arcuate in elevation. The free ends of the arms of this 20 bail holder are designed somewhat angularly, as shown at 21 and are adapted to receive in engagement therewith the upper edge of a strip or plate 22 which is secured to the front faces of the arms 8 at the upper 25 ends of the latter. An additional strip or plate 23 is secured to the rear face of the arms 8 by the same means which secures the strip or plate 22 thereto and the outer ends of the strip or plate 23 are bent upwardly, 30 as shown at 24 to form stops or guides, whereby to retain the arms of the bail holder 20 in position when the same is lowered. The bail holder 20 straddling as it does, the one arm of the bail and engaged with the 35 members at the upper ends of the arms 8, will, obviously, prevent the rotating of the arms 2 in the lower ends of the arms of the bail, 1, which is understood to be held substantially stationary in an upright position, 40 as shown in Fig. 1 of the drawings and the crucible is thus retained in an upright position. By raising the bail holder 20, however, and sliding the block 18 in a direction toward the ring 5, said bail holder is disposed to its ineffective position and the 45 arms 2 may then be rotated in the arms of the bail 1, whereby to upset the crucible for obvious purposes. In view of the particular manner of applying my improved device to 50 use, it will be seen that the crucible will, at all times, be held securely in position in the circular portion of the shank.

In Fig. 8, I have shown a slightly modified form of my invention, particularly 55 adapted for use in smaller work, where no crane is used. In this form of the device, a shank 25 is provided having a central ring or band-like section 26 formed therein to receive a crucible 27. Slidably mounted on 60 one arm of the shank, is a ring-like member 28, similar to the member 5 described in the first mentioned form and pivotally carried on this ring-like member is an arm 29, the outer end of which is designed angularly, as 65 shown at 30, to form a clamping or engag-

ing hook adapted to be engaged with the upper end of said crucible. Ring members 31 and 32 are loosely applied over the arm 29 and the arm of the shank 25, and in view of the inclination of said arm 29, when the hook portion thereof is effectively engaged with the crucible, these ring members may be disposed on the arms to bind tightly thereon. When so disposed, it is apparent 70 that the arm 29 will be securely locked in its operative position to secure the crucible in the band or ring portion 26 of this shank. The shank with the crucible securely held therein, may then be carried from place to place and operated, as desired. 75

From the foregoing description of the construction of my improved device, the operation thereof will be readily understood and it will be seen that I have provided a device which is simple and durable in construction, inexpensive to manufacture and 80 one which will be very efficient and useful in operation.

While I have particularly described the elements best adapted to perform the functions set forth, it is obvious that various changes in form, proportion and in the minor details of construction may be resorted to without departing from the spirit or sacrificing any of the principles of the 95 invention.

Having thus described this invention, what is claimed is:—

1. In a device of the class described, the combination with a bail and a shank mounted for rotation in the arms thereof; of an arm pivotally supported at one end thereof on said shank, the opposite end of said arm being bifurcated to form a straddling portion thereon, the free end portion of said straddling portion terminating in a pair of parallel and vertical arms, a clamping member adjustably carried between said last mentioned arms, adapted for engagement with an object carried by the shank, means to securely clamp the first mentioned arm to the shank, and means slidably mounted on said first mentioned arm adapted for contact with one arm of said bail whereby to prevent the rotation of the shank therein. 100

2. In a device of the class described, the combination with a bail and a shank mounted for oscillation in the arms thereof; of an arm pivotally supported at one end thereof on said shank, the opposite end of said arm having a fork-like straddling portion joined thereto, said straddling member terminating in a pair of vertical parallel arms, a hook-like member adjustably carried between said last mentioned arms and adapted for engagement with an object carried by the shank between the arms of the bail, transverse plates secured to the upper ends of the arms of the straddling member, means to secure the first mentioned arm to 105

the shank to prevent movement of the former with respect to the latter, a sliding member carried on the first mentioned arm, and a bifurcated arm carried by said sliding member adapted to straddle one arm of the bail, to prevent the rotation of the shank and parts carried thereby in the bail, the free end of said bifurcated arm being adapted to rest on the transverse plates at the upper end of said straddling member.

3. In a device of the class described the combination with a bail and a shank mounted for rotation in the arms thereof; of an arm pivotally supported at one end thereof on said shank, a fork-like straddling member curved compoundly and joined to the opposite end of said pivoted arm, the free end portion of said straddling member terminating in a pair of vertical parallel arms, a hook-like member mounted for vertical adjustment between the arms of said straddling member and adapted to engage an object supported on the shank between the arms of said bail, ring members carried on the first mentioned arms and also encircling said shank, whereby to secure said arms and parts carried thereby to the shank, a sliding member mounted on said first mentioned arm, a Y-shaped arm pivotally carried on said sliding member and adapted to straddle one arm of said bail to prevent the rotation of the shank and parts carried thereby, and plates carried on the upper ends of the straddling member adapted to receive the free ends of the arms of the Y-shaped member in contact therewith to afford a rest for the latter.

4. In a device of the class described, the

combination with a shank adapted to support an object; of an arm pivotally carried thereon having a hook-like portion formed on the free end thereof adapted to engage an object carried by the shank, and means loosely carried on said arm for engagement with the shank to secure said arm in its effective engaging position.

5. In a device of the class described, the combination with a shank adapted to support an object thereon; of an arm slidably and pivotally supported on said shank, a hook-like member formed on the free end portion of said arm adapted for engagement with an object carried on the shank, and ring members loosely carried on said arm and also encircling said shank to be moved into frictional engagement with the arm and shank, whereby to lock said arm in its effective engaging position.

6. In a device of the class described, the combination with a shank adapted to support an object; of an arm pivotally and adjustably carried thereon, a hook-like member adjustably connected to the free end portion of said pivotal and adjustable arm adapted for engagement with an object carried by the shank, and means carried on said arm for engagement with the shank to secure said arm in its effective engaging position.

In testimony whereof I hereunto affix my signature in the presence of two witnesses.

HERMAN BEULKE.
